KNIFE OR SIMILAR ARTICLE OF FLATWARE

Irwin Schneider, Lincolnwood, Ill., assignor to Imperial Arts Corporation, Chicago, Ill.

Filed Oct. 26, 1970, Ser. No. 25,676

Term of patent 14 years

Int. Cl. D7—03

U.S. Cl. D95—3

FIG. 1   FIG. 2   FIG. 3

FIG.4

FIG.5

FIG. 1 is a bottom plan view of a knife or similar article of flatware showing my new design;

FIG. 2 is a side elevational view thereof, the opposite side being a mirror image thereof;

FIG. 3 is a top plan view thereof;

FIG. 4 is a cross-section view taken along the lines 4—4 of FIG. 2; and

FIG. 5 is a cross-section view taken along the lines 5—5 of FIG. 2.

The essential features of my design for a knife or similar article of flatware reside in the configuration of the handle in combination with the particular pattern of surface ornamentation as applied thereto.

The design is intended for use on sets comprising forks, spoons, knives, and similar articles of flatware.

I claim:

The ornamental design for a knife or similar article of flatware, as shown and described.
